United States Patent Office.

ALEXANDER McLEOD, OF COVINGTON, KENTUCKY.

Letters Patent No. 74,926, dated February 25, 1868.

IMPROVED RAILWAY-SWITCH STAND.

The Schedule referred to in these Letters Patent and making part of the same.

TO WHOM IT MAY CONCERN:

Be it known that I, ALEXANDER McLEOD, of Covington, Kenton county, and State of Kentucky, have invented a certain new and useful Switch-Stand; and do hereby declare the following to be a full, clear, and exact description thereof, reference being had to the accompanying drawings, making part of this specification.

This invention relates to a construction of switch-stand, target, and shot-bolt, with their accessories, which combines strength with security.

The accompanying drawing is a perspective view of a switch-stand, a portion of the frame being removed.

A A' are two U-formed plates, constituting the frame-stand proper, secured to a sill or cross-tie, B. C is the target, attached to said stand, and bent backward at bottom, C', and attached to the sill B, so as to constitute a very effectual brace to the frame in addition to its proper functions. The two plates A A' serve to hold and guide the switch-bar D, having two or more notches, d d' d'', according to the number of positions it is required to assume. Cross-bars a a' attached to the plates A A', and the target C, afford journal-bearings for the switch-lever E, which lever is pivot-bolted to the switch-bar, and surmounted by a customary movable target, e. F is a shot-bolt, restricted to vertical play by suitable guides, a'' a'', in the frame. The said shot-bolt has a projecting tongue, f, which is subject to the downward pressure of a spiral spring, G, and to the upward pressure (which it is desired to retract the bolt) of a pedal, H. The said bolt F has also, just below its upper guide, an orifice, f', for a padlock, I, by which the bolt may be secured against mischievous or accidental misplacement, and as this lock cannot be applied, save when the bolt is in one or other of the notches, the switchman is always made aware of such unsafe condition of the apparatus. The shot-bolt may be surmounted by a weight, J, to act either in co-operation with or in substitution of the spring G.

I claim herein as new, and of my invention—

The arrangement of stand A A', a a', target C C', switch-bar D, lever E, shot-bolt F, f f', pedal H, and spring G, or weight J, as and for the purpose set forth.

In testimony of which invention, I hereunto set my hand.

Witnesses:

GEO. H. KNIGHT,

JAMES H. LAYMAN.

ALEXANDER McLEOD.
